UNITED STATES PATENT OFFICE

GUY E. RIEGEL, OF SPOKANE, WASHINGTON

DESIGN FOR A RADIOCABINET

Application filed July 25, 1931. Serial No. 40,685. Term of patent 7 years.

To all whom it may concern:

Be it known that I, GUY E. RIEGEL, a citizen of the United States of America, residing at Spokane, in the county of Spokane and State of Washington, have invented a new, original, and ornamental Design for a Radiocabinet, reference being had to the accompanying drawing, forming a part thereof,

which shows a perspective view of the cabinet of my new design.

The opposite side of the cabinet is plain.

I claim:

The ornamental design for a radiocabinet, as shown and described.

GUY E. RIEGEL.
